UNITED STATES PATENT OFFICE

MAX PAUL ERNST HOHN, OF DRESDEN, GERMANY, ASSIGNOR TO "UNIVERSELLE" CIGARETTENMASCHINENFABRIK J. C. MULLER & CO., OF DRESDEN, GERMANY

CIGARETTE-MAKING MACHINE

Application filed January 23, 1928, Serial No. 248,844, and in Germany January 25, 1927.

When the continuous extruded string or rod delivered by the cigarette-making machine is cut through by means of a sickle-shaped knife or cutter which executes a revolving or circulating movement and comes into engagement with the continuous string once in the course of its circuit, the sickle-shaped cutter may be caused to revolve in a plane. In this case the carrier of the sickle-shaped cutter must be so controlled that it executes a reciprocating movement in the direction of the continuous rod, in order that the sickle-shaped cutter, on cutting into the continuous rod, shall take part in the motion of the rod in the direction of travel and at the same speed as the latter. The same effect may be obtained, however, with a stationary sickle knife-carrier, by not letting the sickle knife revolve in a plane but effecting the revolution of the sickle knife along a helical line or letting the sickle-knife-carrier execute a wobbling movement about its axis of rotation. In this case also the sickle knife follows the string in its direction of feed, during the cut, and with the velocity of feed of the string.

As is shown, the sharpening and whetting of the sickle knife must take place while the machine is running. For this purpose the sickle knife comes into contact with a grinding means and a whetting means, once at the completion of each circuit after effecting the cut.

When the sickle knife revolves in a plane, no special controlling of the grinding and sharpening means is required. These means may be simply arranged on the slide which carries the sickle-knife carrier, and it is only necessary to adjust the grinding and whetting means, which consist of freely rotatable rollers or discs, to a suitable obliquity, in order that it may be able to follow the receding cutting edge of the sickle knife as it passes.

If, however, it is a question of a sickle knife which is moved in a helical line or executes a wobbling movement with its carrier, the grinding means and the whetting means must be correspondingly controlled.

The invention relates to a controlling de-

vice which moves the grinding means and the whetting means simultaneously from a single crank gear in such a way that the grinding means and the whetting means adapt themselves during engagement with the sickle knife, not merely to the receding cutting edge of the sickle knife but also to the helical turn or to the wobbling movement.

According to the invention the carrier for the grinding means consists of a swing lever with an adjustable fulcrum, which, in a manner known in itself, is caused by a crank gear, to swing against the sickle knife blade, the carrier of the whetting means being connected with the swing lever by a controlling gear, so that the grinding means and the whetting means, each of which is mounted with a suitable obliquity, are pressed by the controlling of the crank gear, as the sickle knife passes, against the cutting edge thereof, from the corresponding side, in such a way that they follow the receding cutting edge, which, at the same time is executing the helical turn or the like.

With this construction of the carrier for the whetting means it is immediately possible to arrange the said swing lever displaceably and adjustably upon a bracket, the said bracket preferably being arranged in the neighbourhood of the fulcrum of the swing lever.

The controlling of the whetting means may be made more delicate by mounting the carrier of the whetting means rotatably on a supporting piece and effecting the rotation of the carrier by a controlling lever which is moved by means of a connecting rod from the swing lever which carries the grinding means.

This construction of the new device is illustrated in the accompanying drawings, Figure 1 being a side elevation thereof. Figure 1^a is a view from above; Figure 1^b is a special view thereof. Figures 2 and 3 are views of parts of the apparatus, Figure 2 being a view looking in the direction of the arrow A indicated in Figure 1, while Figure 3 is a view looking in the direction of the arrow B in Figure 1.

Figure 1^a shows in a view from above the cooperation of the grinding and whetting means. The knife carrier 45 is formed in the known manner as a wobbling disc. It is adapted to swing on the knife carrier shaft 47 by means of the bolt or pin 46 and to be adjusted by means of the screws 48, 49 i. e. more or less inclined to the longitudinal axis of the knife carrier shaft. The sickle knife 50 is in its lowest position in Figure 1^a and approaches the grinding disc 22. After the bevel or face of the sickle knife 50 has been ground on the correspondingly inclined grinding disc 2 (Figure 1^b) the sickle knife, during its further movement, moves past the whetting disc 32, the rear side of the knife moving along the whetting disc, whereupon the knife is whetted.

Figures 4 and 5 show in side elevation and in plan a second constructional form of the arrangement and of the control for the carrier of the whetting means.

In the closed casing 1 containing the drive and filled with oil, is provided a crank disc 6, driven from a driving shaft 2 by gear wheels 3, 4 and 5. Upon a crank pin 7 on this crank disc 6 is mounted a guiding link 8, which is pivotally connected at 9 to a crank rod 10. This rod passes through the wall of the casing with suitable packing and is here satisfactorily guided by a long guiding piece 11. To the end of the rod 10 is pivoted by means of a bolt 12, a guiding link 13, which is pivotally connected at the other end with a swing lever 14. This swing lever swings about a bolt 15, and its oscillation is brought about by the reciprocating movement of the crank rod 10. The bolt 15 is carried by a downwardly projecting bracket 16 of a slide piece 17 which is displaceable by the aid of a screw-threaded spindle 18. This screw-threaded spindle is rotatably held at 19 to a guide. The rotation of the spindle is effected by means of a handwheel 20. Accordingly the pivot bolt 15 of the swinging lever 14 can be shifted against the cutting blade, which is indicated by a dotted line, as the swing lever 14 also executes its swinging movement against this knife blade. The swing lever 14 carries the bearing 21 for the grinding disc 22. The grinding disc 22 is mounted upon a rotatable spindle 23, which passes through a bearing eye 24. The bearing body 21 is mounted by a base plate 25 upon a head plate 26 of the lever 14, the connection being effected by screws or the like, in such a way that no rotation of the bearing 21 about its vertical axis is possible, and accordingly accurate adjustment of the guiding surface to the cutting edge of the sickle knife blade can take place.

Now upon the pivot bolt 12 (see also Figure 3) is rotatably mounted a connecting rod 27. This is attached at its other end to a pivot pin 28, which is rotatably mounted on

a lever 29. The lever is screwed at its upper end to a bracket 30 extending downwards from the carrier 31 that carries the whetting disc 32 (see also Figure 2). The whetting disc is freely rotatable and is mounted with its spindle in a bearing eye 33. The carrier 31 is rotatably mounted upon a journal 34, one flattened end of which is inserted in a guiding slot 35 in a carrying arm 36 and can be clamped at the desired height by screws 34¹. The guiding arm 36 is bent at right angles, the bent part 37 passing through a horizontal guide 38. By means of a screw-threaded spindle 39 and a handwheel 40, the guide piece 36 can be shifted and adjusted 80 in the guide 38.

By the crank rod 10 the grinding disc 22 is pressed against the cutting edge of the sickle knife at the instant when the sickle knife comes within its reach. The correct adjusting of the bolt 15 provides under these circumstances for an appropriate oblique position of the grinding surface, in order that the latter may bear correctly against the facet of the sickle knife.

The further controlling by the crank rod 10 yields the result that the grinding surface not only follows the receding cutting edge but also participates in the helical movement or the wobbling movement.

The whetting disc 32 is first correctly adjusted by the aid of the guide 38 in relation to the plane of the knife blade. It is furthermore so moved, by rotating its carrier 33 by means of the swing lever 29, that, on engaging with the cutting edge of the sickle knife it follows the retreat of the said cutting edge, as well as the wobbling movement.

In the construction according to Figures 4 and 5 a bracket 41 is screwed to the swing lever 14, which is controlled by the crank rod 10 and carries the carrier 21 of the grinding means 22, in the neighbourhood of the fulcrum 15. The carrier 33 of the whetting means 32 is mounted on this bracket 41 in such a manner that it can be shifted and clamped in a manner known in itself, the entire carrier being rotatable by means of a screw bolt 42, and the screw bolt passing through a slot 43, which is indicated in Figure 4, and which enables the carrier 33 to be raised and lowered. Furthermore the sleeve 44 passing transversely through the carrier 33 can be axially adjusted and clamped in relation to the spindle of the whetting means 32 passing through this sleeve.

In this construction the whetting means 32 participates in the controlling movement of the swing lever 14.

What I claim is:

1. Apparatus for controlling the grinding and whetting means for the sickle knives of string cigarette machines, comprising a sickle knife for cutting up the cigarette strings into separate cigarettes, said sickle knife

being adapted to follow the string in the direction of feed of the string and with the velocity of the string during the execution of the cut, obliquely positioned grinding means for said sickle knife, a swing lever carrying said grinding means, obliquely positioned whetting means for the sickle knife, a carrier for said whetting means, controlling means connecting said whetting-means carrier with the swing lever and crank gear adapted to rock the swing lever so as to move the grinding means and the whetting means into contact with the cutting edge of the sickle knife in passing and to cause said grinding means and said whetting means to follow the cutting edge and remain in contact with it as it recedes from them.

2. Apparatus for controlling the grinding and whetting means for the sickle knives of string cigarette machines, comprising a sickle knife for cutting up the cigarette string into separate cigarettes, said sickle knife being adapted to follow the string in the direction of feed of the string and with the velocity of the string during the execution of the cut, obliquely positioned grinding means for said sickle knife, a swing lever carrying said grinding means, means for displacing the fulcrum of said swing lever, obliquely positioned whetting means for the sickle knife, a carrier for said whetting means, controlling means connecting said whetting-means carrier with the swing lever and crank gear adapted to rock the swing lever so as to move the grinding means and the whetting means into contact with the cutting edge of the sickle knife in passing and to cause said grinding means and said whetting means to follow the cutting edge and remain in contact with it as it recedes from them.

3. Apparatus for controlling the grinding and whetting means for the sickle knives of string cigarette machines, comprising a sickle knife for cutting up the cigarette string into separate cigarettes, said sickle knife being adapted to follow the string in the direction of feed of the string and with the velocity of the string during the execution of the cut, obliquely positioned grinding means for said sickle knife, a swing lever carrying said grinding means, obliquely positioned whetting means for the sickle knife, a carrier for said whetting means, a slidably arranged carrier on which said whetting means carrier is rotatably supported, a second swing lever engaging with the whetting-means carrier, a crank interposed between the two swing levers to enable the first swing lever to control the second and thereby to rotate the whetting-means carrier, and crank gear adapted to rock the swing lever so as to move the grinding means and the whetting means into contact with the cutting edge of the sickle knife in passing and to cause said grinding means and said whetting means to follow the cutting edge and remain in contact with it as it recedes from them.

follow the cutting edge and remain in contact with it as it recedes from them.

4. Apparatus for controlling the grinding and whetting means for the sickle knives of string cigarette machines, comprising a sickle knife for cutting up the cigarette string into separate cigarettes, said sickle knife being adapted to follow the string in the direction of feed of the string and with the velocity of the string during the execution of the cut, obliquely positioned grinding means for said sickle knife, a swing lever carrying said grinding means, obliquely positioned whetting means for the sickle knife, a carrier for said whetting means, a slidably arranged carrier on which said whetting-means carrier is rotatably supported, said slidably arranged carrier being formed with a guiding slot, a pivot for the whetting-means carrier, said pivot being adapted to slide in said guiding slot and to be clamped therein, a second swing lever engaging with the whetting-means carrier, a crank interposed between the two swing levers to enable the first swing lever to control the second and thereby to rotate the whetting-means carrier, and crank gear adapted to rock the swing lever so as to move the grinding means and the whetting means into contact with the cutting edge of the sickle knife in passing and cause said grinding means and said whetting means to follow the cutting edge and remain in contact with it as it recedes from them, said crank gear comprising a reciprocating crank rod, a pivot bolt at one end of said crank rod, a lever link connecting said pivot bolt to the first swing lever, and a crank connecting said pivot bolt to the second swing lever.

In testimony whereof I have signed my name to this specification.
